UNITED STATES PATENT OFFICE.

AUGUST BUERKLE, OF ALLEGHENY, PENNSYLVANIA.

DESIGN FOR A CASE OR SHELL FOR WATER-HEATERS.

SPECIFICATION forming part of Design No. 29,584, dated November 1, 1898.

Application filed September 19, 1898. Serial No. 691,382. Term of patent 14 years.

To all whom it may concern:

Be it known that I, AUGUST BUERKLE, a citizen of the United States, residing at Allegheny, in the county of Allegheny and State of Pennsylvania, have invented and produced a certain new and original Design for a Case or Shell for Water-Heaters, of which the following is a specification.

In the accompanying drawing, forming a part of this specification, is shown a perspective view of my new design for a case or shell for water-heaters.

The leading feature of the design is a case or shell having the side walls or panels 1, the

double-wing doors 2 at the ends of the case 15 or shell, and a sliding door 3 about midway of the height of one of the side walls or panels. The doors 2 are curved, thereby giving a circular contour to the ends of the case or shell.

I claim as my invention—

The design for a case or shell for water-heaters, as herein shown and described.

In testimony whereof I have hereunto set my hand.

AUGUST BUERKLE.
